UNITED STATES PATENT OFFICE.

CHARLES C. AVERILL, OF TREES, LOUISIANA.

WELL-DRILLING RIG.

1,208,891.

Specification of Letters Patent. Patented Dec. 19, 1916.

Application filed April 17, 1916. Serial No. 91,542.

To all whom it may concern:

Be it known that I, CHARLES C. AVERILL, a citizen of the United States, residing at Trees, in the parish of Caddo and State of Louisiana, have invented a certain new and useful Improvement in Well-Drilling Rigs, of which improvement the following is a specification.

This invention relates to rigs for drilling wells, and more particularly to what are known as "Standard" rigs and "combination" rigs used for drilling oil wells, and in which a derrick is employed. With these forms of rigs as heretofore used, hoisting drums, such as the so-called "bull wheel" and the "calf wheel", have been mounted at one or more sides of the derrick, and upon its foundation, but an additional foundation has been employed extending out from one side of the foundation of the derrick for supporting a driving wheel for operating the walking beam, sand reels, and other drums or wheels for various purposes. This additional foundation requires considerable space and a large amount of extra timber, which is expensive, while much additional labor is also required in its construction.

One of the objects of my invention is to provide a rig in which substantially all the wheels, hoists, and other operating parts are mounted on the derrick foundation, thereby greatly reducing the cost of construction and the amount of space and material required.

Another feature of my improvement relates to the means for driving the walking beam, and a rotary by a crank shaft located near or beneath the derrick floor and having suitable sprocket wheels.

Another feature comprises a line shaft mounted on upright derrick members across one side of the derrick foundation and a plurality of drums located above said shaft at the same side of the derrick and adapted to be driven thereby.

Another feature comprises a pivot for the lower end of the samson post, whereby a short walking beam may be employed, and the end thereof will move in substantially a straight line. This feature may be used for drilling with cable and tools system, or for pumping after the drilling is completed.

These and other features will now be more fully described in detail, and the points of novelty will be set forth in the appended claims.

In the accompanying drawings: Figure 1 is a plan of the base of a derrick with one form of my improved drilling rig; Fig. 2, a side elevation of a portion of the derrick showing the driving connection for the walking beam; Fig. 3, an elevation of one of the adjacent sides of the derrick showing the power or line shaft and the several hoisting drums that may be driven thereby; Fig. 4, a vertical section through the derrick and showing the walking beam and crank shaft in side elevation; and Fig. 5, a similar sectional view showing a rotary rig and the driving connection from the crank shaft.

My improvement is shown as applied in connection with the usual form four legged derrick with a square foundation or base constructed of main sills, 6, cross sills, 7, floor beams or stringers, 8, and flooring, 9.

A power or line shaft, 10, is mounted in bearings on the upright members on the derrick base and across one side thereof near the floor, said shaft being preferably driven by an engine or other motor, 11, connected directly at one end of the shaft by means of a flexible coupling. Above the shaft and parallel therewith, upon the same side of the derrick are mounted the hoisting drums, one or more, three being shown in Fig. 3 of the drawing, the drum, 12, which may be used for bailing with the standard rig, the drum, 13, for hoisting tubing, etc., of a rotary rig, and the drum, 14, used with the usual cable and tools of a standard rig. These drums are mounted on separate shafts adapted to be driven independently of each other by means of suitable clutches, sprocket wheels and drive chain connections from the line shaft, 10. The drums are also each provided with the usual brake bands and wheels. By thus locating the line shaft below the hoisting drums and nearer the floor of the derrick, a more rigid bearing is provided for said shaft and the objectionable vibration is thereby avoided.

The walking beam, 15, is pivotally mounted on the samson post, 16, and is operated by a pitman, 17, pivoted on the crank sprocket wheel, 18, mounted on the crank shaft, 19, which is supported in bearings on the base of the derrick, near or below the floor, and is driven by a chain from the line shaft, operating on sprockets, 20 and 18. The crank wheel, 18, is provided with a plurality of holes at different distances from its center for shifting the connecting pin of

the pitman to vary the length of the stroke of the walking beam.

In order that the end of the walking beam may travel in substantially a straight line during its oscillating movements, the samson post, 16, may be mounted on a pivoted bearing, 21, whereby the same may swing forward and backward a slight distance to compensate for the inward and outward movement of the end of the beam in oscillating on its pivot. The braces, 22, are pivotally attached at one end to the top of the walking beam, and at the other end to the floor at some distance, for steadyng and guiding the samson post. This feature of providing for a straight line movement is especially important after the well is finished, for operating the rod, 27, of the pump. A universal link connection, 23, is provided between the upper end of the pitman and the walking beam, whereby the pitman may swing both transversely and longitudinally of said beam and thereby prevent any binding action on the connecting pin.

My improvement is also adapted to operate a rotary, 26, by means of a sprocket, 25, and a chain driven from a sprocket wheel, 24, on the crank shaft, 19, as shown in Fig. 5. The size of the sprocket wheels for the several drives may be readily changed at any time to give the desired speed ratio.

It will now be seen that my improved construction may be used either as a standard rig with cable and tools, or as a combination rig including the rotary hydraulic system, and that substantially all parts of the apparatus are contained within the space of the derrick foundation and supported upon its base.

Having now described my invention, what I claim as new and desire to secure by Letters Patent is:

1. In a well drilling rig, the combination with a derrick having a substantially rectangular base, of a power shaft mounted in bearings along one side of said base, a crank shaft at the middle portion of one of the other sides of said base, a driving connection between said shafts, a walking beam mounted on said base, and operated by said crank shaft, and one or more hoisting drums mounted above said power shaft and operated thereby.

2. In a well drilling rig, the combination with a derrick having a substantially rectangular base, of a power shaft mounted in

bearings along one side of said base, a crank shaft mounted at the middle portion of one of the other sides of said base, and extending beneath the floor of the derrick, a driving connection between said shafts, a rotary drilling device, and a driving connection from said crank shaft to the rotary.

3. In a well drilling rig, the combination with a derrick having a substantially rectangular base with upright members at the corners thereof, of a samson post mounted on the derrick floor within the uprights, a walking beam pivotally mounted on said post, a crank shaft mounted on the derrick base, a pitman connecting said crank shaft and walking beam, and driving mechanism for operating said crank shaft.

4. In a well drilling rig, the combination with a derrick having a base and upright members at the corners thereof, of a power shaft mounted in bearings along one side and supported on said base, a motor connected at one end of said shaft, one or more hoisting drums driven from said shaft, a crank shaft also mounted on said base within the uprights and parallel with said power shaft, and a driving connection between said shafts.

5. In a well drilling rig, the combination with a derrick having a base and upright members at the corners thereof, of a power shaft mounted in bearings along one side and supported on said base, one or more hoisting drums driven from the power shaft, a crank shaft also mounted at the middle portion of one of the other sides of said base parallel with the power shaft, and having a crank, a walking beam also substantially parallel with said shafts, and a pitman connected to the crank and the walking beam.

6. In a well drilling rig, the combination of a samson post hinged at its base, a walking beam mounted on said post, and braces pivotally connected to the walking beam at a point above the samson post and to a support.

7. In a well drilling rig, the combination with a derrick having a floor, of a samson post hinged at its base to said floor, a walking beam mounted on the samson post, and braces pivotally connected at one end to the walking beam at a point above the samson post and at the other to said floor.

In testimony whereof I have hereunto set my hand.

CHARLES C. AVERILL.
